CIGARETTE EXTINGUISHER

Anthony J. Millett, Shaker Heights, Ohio

Application January 23, 1943, Serial No. 473,307

1 Claim. (CL 131—4)

It is a well established fact that annually, life and property damage caused by smokers is tremendous. A cigarette extinguisher at the finger tips will afford great comfort to the average smoker, and society, in the knowledge that such losses due to everyday negligence and carelessness can be cut to a minimum.

With this in view, I have constructed a cigarette extinguisher cheap to make and simple to assemble in a foolproof manner, which has as its primary object, a construction which will permit of its ready adaptation to various sizes and shapes of cigarettes.

Having briefly outlined my improved construction, I will proceed to describe the same in detail, reference being made to the accompanying drawing, in which I have illustrated an embodiment thereof.

In this drawing:

Figure 1 is a perspective view of a cigarette 20 having thereon my extinguisher comprising a lid and a tab.

Figure 2 is an end view of Figure 1.

Figure 3 shows the band with the lid and tab projecting outwardly from the burning end of 25 the cigarette.

Figure 4 shows the opposite side of the band of Figure 3 illustrating the slot at the extremity of the band.

Figure 5 shows the extremity of the band 30 capped.

Referring in detail to the drawing, numeral 1 designates the paper wrapper of a cigarette having thereon the slidable band 3 equipped with a lid 5 and a tab 4. Numeral 2 designates the 35 tobacco filler.

The normal position of the extinguisher when furnished on cigarettes is as shown in Figure 1. The tab 4 is secured sufficiently to the band 3 so that upon grasping the tab 4 it will separate from the band 3 providing a handle for manipulation of the band and lid, without the danger of burning one's fingers or the necessity of directly grasping the band which when slid over the burning end of a cigarette might prove harmful.

If the cigarette shown in Figure 1 is lighted it will burn freely to a point within the band 3 and will then go out, owing to lack of air circulation. The band 3 can be used to snuff out 50

the fire at any point of the cigarette by pulling the tab 4 from its secured position and sliding the band 3 over the burning end of the cigarette 7 as shown in Figure 3. I prefer this method used when a smoker is extinguishing a cigarette and laying it in an ash tray, for the burning tobacco will generally not come loose and the cigarette will extinguish itself without the danger of smoldering, as is the case in most methods of extinguishing a burning cigarette. However if a burning cigarette is to be discarded outside of an ash tray I prefer the method as illustrated in Figure 5. The tab 4 is brought around the end of the band 3 so that the lid 5 will cap the end of the band 3 and may be held fast by inserting the tab 4 into the provided slot 6 causing rapid extinguishment and safety against hot ashes or loose burning tobacco escaping upon the discardment of a burning cigarette. Figure 4 show the slot 6 into which the tab 4 is inserted.

Undoubtedly enormous advantages may be obtained from the use of this band, such as fire protection, economy, comfort, and convenience. The band can also be used for a fingerhold, preventing stain, or as a mouthpiece.

Obviously numerous modifications of structure might readily be resorted to without in the least departing from the spirit of my invention.

Having described my invention, I claim:

A cigarette extinguisher comprising a band of fire resistant material of such length as to pass around and to closely embrace a cigarette, an overlapping lid or cover, and a tab integral with the material of the band and a slot formed on the opposite side of the band so that when the tab and adjoining lid are passed around the end of said band the lid will cap the extremity thereof and may be held fast by the tab inserted into the provided slot, whereby a cheap unitary cigarette extinguisher is formed which provides a close embrace about the lighted end of a cigarette to extinguish it and the tab provides a handle for manipulation of the band and lid, for the purpose of capping the band, thereby causing rapid extinguishment and safety against hot ashes or loose burning tobacco escaping upon the discardment of the burning cigarette.

ANTHONY J. MILLETT.
